REFRIGERATOR VENTILATOR

James C. Procter, Cumberland, Ind.

Application July 29, 1953, Serial No. 371,138

3 Claims. (Cl. 62—89)

This invention relates to a device for preventing un-
due frost formation over the walls and around door
openings in a refrigerator of the "walk in" type such as
is used as hardening rooms, wherein the temperature is
kept well down below zero, for example such as around
10° F. below.

In many of these types of refrigerators, considerable
difficulty has been occasioned in keeping the insulation
dry, and in preventing excessive frost from accumulating
on the walls of the room, and particularly in preventing
frost from accumulating around the door to such an ex-
tent that the door is exceedingly difficult to open.

These types of refrigerators are subject to air in-
filtration, in that there is a travel of air from the outside
to the inside of the refrigerator, meaning that the moist
air from outside infiltrates through the insulation to tend
to equalize the internal pressure with the outside, due
to the fact, that in cooling the air within the refrigerator
room, this cooled air assumes less volume thereby tending
to produce an inflow from the outside.

Moisture laden, warm air, upon moving through the
insulation condenses, particularly so as it nears the inner
surface, and thus decreases the insulating value, as well
as setting up a deteriorating effect, particularly where
organic material, such as cork, is used. Also, frost forms
on the interior of the walls of the refrigerator.

Air also leaks or infiltrates in around door edges, and
the frost forming tends to freeze fast the door or other
shiftable closure.

The important object of my invention is to provide
means through which the internal pressure of the re-
frigerator will be equalized without travel of the warm,
moisture carrying external air through the surrounding
insulation and through minute crevices around re-
frigerator doors and the like. In other words, it is an
object of my invention to provide an air travel passageway
open at all times from the atmosphere to within
the refrigerator as the means for pressure equalization.

Further, this pressure equalizing means provides for
condensing and freezing out of the incoming air the major
moisture content thereof, and also provides for removing
the frost from this means to maintain an open pas-
sageway.

In short, I provide a controlled air intake for the re-
frigerator wherein moisture of the air is frozen out
of the air in the zone of that intake to maintain the
insulation in dry state, and to avoid frost and ice ac-
cumulation around doors.

The invention comprises briefly an open tubular element
entering from the outside of the room from the
atmosphere and extending into the room a distance where-
in, under normal closed room conditions, air tending
to enter the room is free to enter through this tube.
The tube is always open throughout its length, extends
within the room far enough to cool the air in the tube,
condense out, and freeze the moisture within the length
of the tube. This tube may be located in any zone about
the refrigerator wherein the best results are found to be
obtained. In the description and drawing herein, the
tube is shown to be located near the room ceiling, but
this location may vary without departing from the spirit
of the invention.

Opening the door of the room, particularly a hinged
door, tends to pull air through the tube into the room,
and closing the door tends to force air from the room
out through the tube. The invention further includes a
structure which will prevent this tube from clogging up

2

with frost in view of the fact that the atmospheric air
generally is carrying considerable moisture, and when
this moisture strikes the interior of the cold end of the
tube, frost will tend to form.

5 One particular form of the invention as now best
known to me is described in the accompanying drawing,
in which

Fig. 1 is a view in vertical section through the upper
end, corner portion of a refrigerator room to which the
10 invention is applied;

Fig. 2 is a view in front elevation in detail on an en-
larged scale of the structure embodying the invention;
and

Fig. 3 is a view in horizontal central section through
15 the structure.

Referring to Fig. 1, there is illustrated in fragmentary
form and in section a portion of the upper ceiling 10
and a downwardly turned portion of the front wall 11
in which there appears a door 12. Through the wall
20 11, preferably near the door 12, there is inserted a tube
13 to extend well within the room itself. This tube 13
may of course vary in size depending upon the size of
the room, and for example, it may have a diameter from
25 three to four inches, and extend into the room from
three to five feet.

When the door 12 is opened, there is tended to be
created within the room, a vacuum which will cause an
inrush of air from the outside through the tube 13 to
discharge interiorly of the room. Conversely, when the
30 door 12 is closed, the air within the room will tend to
be pressurized, and there will be a flow outwardly from
the room through the tube 13 to discharge into the at-
mosphere. In some instances, the provision of the tube
13 to afford communication from the outside with the
35 inside of the room, this means being located near the
ceiling of the room, is sufficient to take care of the
excess moisture condition within the refrigerator. How-
ever, when that moisture becomes excessive, then it is
40 advisable to proceed further and provide for means to
remove frost from the interior surface of the tube 13.

I employ a scraper device of some sort which will
ride over the interior surface of the tube 13 so as to
45 scrape frost off of that surface entirely around the cir-
cumferential face thereof. In the present form, I em-
ploy a coiled wire member 14, in the nature of a coiled
spring, to have the turns 15 spaced apart a distance
50 somewhat less than the distance the member 14 will be
carried in scraping off the frost. This spacing of the
turns is had in order to provide an overlapping travel of
one turn over an area previously traveled or traversed
by an adjacent turn.

Some means has to be employed to set up this travel
of the member 14 to and fro within the tube 13 at periodic
55 intervals, and I accomplish this reciprocating travel by a
suitable connection made with the door 12 so that the
opening and closing of that door 12 will induce the de-
sired travel of the member 14.

There is provided at the outer end of the tube 13 a
60 bracket generally designated by the numeral 16, herein
shown as being bifurcated with an interconnecting web
17 tying together the two arms 18 and 19. These two
arms 18 and 19 extend over the outer end of the tube 13
to substantially the center thereof, and pivotally carry
therebetween at their outer ends a rocker member 20.

This rocker member 20 is formed to have two side
65 plates 21 and 22 interconnected by a web 23. This rocker
member 20 is substantially semicircular in length, and
carries a roller 24 at one end and a roller 25 at the other
70 end revolvably between the plates 21 and 22. The member
20 is rockably supported between the arms 18 and 19 past
the center of the member 20, to have the pivot pin 26
located nearer the roller 25 than it is to the roller 24.
The outer end of the member 14 is interconnected through
75 a leg 27 to the rocker member 20 at any some such point,
herein shown as about an end of the pin 28 which serves
as the axle for the roller 25.

From the web 23 there is extended a tongue 29 between
the plates 21 and 22 to have an end of a spring 30 hooked
therethrough, Fig. 3. The other end of the spring 30 is
engaged in the tongue 31 which extends from the web 17
80 of the bracket 16. This tongue 31 extends between the

plates 21 and 22 at a location between the pivot pin 26 and the roller 25, Fig. 3, being closer to the roller 25 than it is to the pin 26. Also, the locations of the interengagement of the ends of the spring 30 with the tongues 29 and 31 are such that when the rocker member 20 is rocked from the solid line position, Fig. 3, it will be flipped to a dash line position as indicated by reason of the axis of the spring 30 passing to the other side of the pin 26 axis, and reversely when the rocker member is in the dash line position, and pressure is exerted on the roller 25 in a direction toward the end of the tube 13, the spring will flip to the other side of the axis of the pin 26 to cause the rocker member to assume the full line position.

In reference to the pin 26, there is another pin 33 interengaging the plate 22 with the arm 19 of the bracket 16, this pin 33 being axially aligned with the pin 26 so that the spring may travel freely through the rocker member 20 without interference.

In order to set up the reciprocation of this rocker member 20, the door 12 has a member 34 fixed thereto and extending upwardly into the path of the roller 24 as indicated in Figs. 2 and 3. In these positions, the door 12 is closed. When the door is open, the member 34 will travel to and through the dash line position 34a, and in so doing, the roller 24 will be pushed outwardly from the end of the tube 13, until the spring 30 will flip the rocker to the dash line position to have the roller 24 entirely out of the way of the member 34. In so doing the roller 25 follows in and around behind the member 34 to stop at that position as indicated by the dash line to which the numeral 25a is applied. In traveling from the solid line position to the dash line position, this roller 25 will travel that distance which will have pulled the member 14 outwardly along the tube 13 to the positions of turns as indicated by the dash line. Then when the door member 34 comes back again and strikes the roller in the position 25a, the roller 24 will follow around in behind the member 34 and be snapped thereagainst by the spring 30 so that the member 14 is returned to its initial and normal solid line position with a considerable snap action. In this way, frost which may have accumulated around the inside of the tube 13 will be scraped off, and the current of air induced by the closing of the door will shift that frost so that it will no longer adhere to the tube 13, and eventually will be carried out of it. As indicated in Fig. 3, the member 14 terminates immediately adjacent the inner end of the tube 13 so that the member 14 is substantially coextensive with the length of the tube 13.

Again where the frost accumulation may be excessive, the tube 13 may be heated such as by a lamp, placed

within the tube 13 (not shown), the heating effect required being quite small in any event, and in most instances may be dispensed with entirely.

The device is extremely effective in reducing the moisture content of the refrigerated room, and the door 12 may at all times be freely opened and closed without the heretofore difficulty of the door freezing shut. The interconnection between the door 12 and the roller 24 will vary depending upon the position of the door in reference to the location of the tube 13, but in any event there will be some arm or interconnection interposed between the door and the roller 24 to set up the switching of the roller 24 from one position to the other to induce the travel of the member 14.

While I have herein shown and described my invention in the one particular form, it is obvious that structural changes may be employed without departing from the spirit of the invention, and I therefore do not desire to be limited to that precise form beyond the limitations which may be imposed by the following claims.

I claim:

1. A pressure-equalizer for a refrigerated space having an entry door, comprising in combination with said door, a tube entering the space from a non-refrigerated space, through which tube a flow of air is induced by variations of pressure between said spaces; an inner tube wall frost scraper; and means actuated by travel of said door shifting the scraper along said wall.
2. The structure of claim 1 in which said scraper has spaced apart wall contacting members; and in which said scraper actuating means embodies a snap action in kicking the scraper from position to position in said tube.
3. The structure of claim 1 in which said scraper comprises a coiled wire member; and said scraper actuating means comprises an eccentrically mounted rocker having a fixed pivot axis, spring means yieldingly retaining the rocker in one of two positions by reason of the axis of said spring means being rocked to either side of said pivot axis; a door carried member in the path of ends of said rocker; and said wire member having an end connected to said rocker for travel with the rocker.
